(57) **CLAIM**

The ornamental design for a body-worn portable electronic device, as shown and described.

DESCRIPTION

FIG. 1 is a front perspective view of a body-worn portable electronic device showing our new design;
FIG. 2 is a front view thereof;
FIG. 3 is a rear view thereof;
FIG. 4 is a left-side view thereof;
FIG. 5 is a right-side view thereof;
FIG. 6 is a top plan view thereof;
FIG. 7 is a bottom plan view thereof; and,
FIG. 8 is another perspective view thereof, in a closed position, shown on a strap.

(Continued)

The broken line showing of a strap in FIG. 8 illustrates environment; the remaining broken lines illustrate portions of the body-worn portable electronic device. The broken lines form no part of the claimed design. No claim is made to any unshaded surface between a broken and a solid line.
